UNITED STATES PATENT OFFICE

OLE M. PETERSON, OF TURNER, OREGON

AEROPLANE

Application filed August 18, 1927. Serial No. 213,841.

This invention relates to an aeroplane.

It is particularly aimed to provide a novel, generally improved and yet simple construction whereby an aeroplane or flying machine 5 may hover, be efficiently braked while in the air, and will be capable of rising in minimum space.

It is also particularly aimed to provide a novel construction having a plurality of 10 planes capable of independent movement or novel coaction.

A further specific object is to provide a 15 novel construction having propellers at front and rear and capable of forward and reverse movement for novel coaction.

Various additional objects and advantages will be pointed out or become apparent from a consideration of the description following taken in connection with accompanying drawings 20 illustrating of an operative embodiment.

In said drawings:—

Figure 1 is a plan view of an aeroplane constructed in accordance with my invention;

Figure 2 is a side elevation thereof;

25 Figure 3 is a front elevation thereof;

Figure 4 is a rear elevation;

Figure 5 is a sectional view taken transversely on the line 5—5 of one of the planes of Figure 1; and

30 Figure 6 is a plan view of a modified form.

In carrying out the invention, 10 is a conventional fuselage equipped with usual or other rudder or tail steering and sustaining mechanism as at 11. The usual cockpit is at 35 12, and adjacent the same, guide wings 13 movable on horizontal pivots 14 by appropriate mechanism 15, are provided and which wings facilitate guiding and steering generally. The fuselage is provided with ground 40 wheels or the equivalent as at 16.

Appropriately fastened to the fuselage 10 adjacent the forward end is a skeleton superstructure or framework 17 which mounts any desired number of motors or prime movers as 45 at 18, four being shown by way of example. It is obvious that these motors are of any approved type. Each of these motors is of the reversible type, with the reversing mechanism under control of the pilot in the cockpit 50 12, in any suitable way. The central motor

18 operates shaft 19 to which front propellers 20 are keyed. The outer motors 18 drive shaft 21 to which rear propellers 22 are keyed. Due to the reversibility of the motors, the propellers 22 may be driven in either direction desired. 55

A rod or shaft 23 is disposed in a direction transversely of the fuselage and at the top of the superstructure 17. On such rod or shaft 23 and midway of their ends, a main plane 24 and outer or side planes 25 are journaled or pivoted, being relatively close to each other. Means is provided whereby the plane 24 may be swung on the axis of the shaft 23 independently of the swinging of the plane 25 65 from the axis of that shaft. For example, the plane 24 may have a sprocket wheel 26 fixed thereto and a sprocket chain 27 trained thereover and associated with appropriate operating and locking mechanism as at 28 70 under control of the pilot in the cockpit at 12. Likewise each of the planes 25 may have a gear wheel 29 keyed thereto and sprocket chains 30 trained thereover. Sprocket chains 30 are also trained over sprocket wheels 31 75 rigid with a shaft 32 having an operating crank as at 33 so that the pilot may actuate the same in order to adjust the angle of the planes 25 independently of adjustment of the plane 24. Associated with the crank 33 is an 80 appropriate conventional locking mechanism such as 34.

Extending completely across the superstructure 17 intermediate the planes 24 and 25 are baffles 35 of appropriate depth. These 85 baffles serve to avoid interference and separate the lines of air coacting with the front propellers and rear propellers. It is to be understood that the baffles may be carried by the planes if desired rather than by the superstructure 17. 90

At the rear of the plane 24, several small auxiliary planes 37 may be provided to facilitate steering and balancing. These planes are 95 carried by rods 38 suitably journaled in the framework 17 and are adjustable through the actuation of appropriate chain and sprocket mechanism, under control of the pilot from the cockpit and as suggested at 100

39, and which mechanism may be similar to said frame, sustaining planes three in number mounted to swing on said rod to different positions of adjustment, propellers at the rear of the outer planes, a propeller at the front of the intermediate plane, motor mechanism on the frame to operate said propellers, means operable by a pilot from the cockpit to adjust said intermediate plane, and auxiliary planes at the rear of the intermediate plane.

As a result of the construction described, the planes 25 are adjustable in unison but independently of adjustment of the plane 24.

5 This proves most efficient in enabling the rising of the aeroplane in minimum space or alighting therein as the planes will coact on a kite-like principle since the propellers 18 and 22 force air thereunder when such propellers are at an angle when the aeroplane is rising. At proper adjustment, the aeroplane will be held practically braked against forward movement by the propellers 22 which in such instance operate in reverse forcing air ahead while the propellers 18 are forcing air to the rear. Under such conditions the baffle plates 35 keep the air current separate or from interfering with each other so that maximum efficiency is attained both for lifting and for carrying. Particularly when the rear propellers 22 are reversed, they act as a brake causing the aeroplane to hover or stop in a short distance or 20 remain substantially stationary in the air without falling.

It is to be understood that the means illustrated for accomplishing the different functions and ends has been detailed by way 30 of example only and that no limitation thereto is to be implied since various changes may be made and equivalent views without departing from the spirit and scope of the invention.

35 The braking feature may well be used on aeroplanes of the type using a rotating propeller for rising straight up in the air and also with present ordinary wings when used as braking or stopping short only. For instance a present type of stationary aeroplane is suggested in plan in Figure 6. Referring to that figure the main plane of the aeroplane is shown at 50 having at 51, a suitable lifting propeller driven by a shaft 52 vertically disposed. Coacting therewith, are forward propellers 53 and rear propellers 54 corresponding respectively with the propellers 18 and 22, being reversible and driven from any suitable source of power.

40 50 It may be mentioned that the planes or wings 24 and 25 may be of any appropriate construction, that is of a light wood or metal framework covered with canvas or they may be of light metal or otherwise. As 55 well they may be reenforced by framing as at 40.

I claim as my invention:—

1. An aeroplane having a frame, a rod on said frame, sustaining planes three in number mounted to swing on said rod to different positions of adjustment, propellers at the rear of the outer planes, a propeller at the front of the intermediate plane, motor mechanism on the frame to operate said propellers.
2. An aeroplane having a frame, a rod on

In testimony whereof I affix my signature.
